UNITED STATES PATENT OFFICE.

EDWARD L. PITTS, OF CINCINNATI, OHIO.

DESIGN FOR A GAME DEVICE.

52,288.

Specification for Design. Patented Aug. 20, 1918.

Application filed March 6, 1917. Serial No. 152,950. Term of patent 3½ years.

To all whom it may concern:

Be it known that I, EDWARD L. PITTS, a citizen of the United States, residing at Cincinnati, in the county of Hamilton and State of Ohio, have invented a new, original, and ornamental Design for a Game Device, of which the following is a specification, reference being had to the accompanying drawing, forming part thereof.

My new, original and ornamental design for a game device is shown in the accompanying drawing, in which—

The figure is a front elevation of a game device, showing my new design.

I claim:

The ornamental design for a game device, substantially as shown.

EDWARD L. PITTS.

Witnesses:

CHARLES E. WEBER,
R. W. SMITH.
